UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

CONVERSION OF HYDROCARBON GASES

Application filed April 8, 1931. Serial No. 528,530.

This invention relates to a process for the conversion of hydrocarbons, to produce lighter products therefrom, such as acetylene or similar gases and liquid motor fuels.

More specifically, the invention relates to the conversion of hydrocarbon gases such as those produced in an oil cracking process and others, said conversion being influenced by the action of ultra violet light and resulting in the production of acetylene or similar gases and motor fuels.

In one specific embodiment of the invention, hydrocarbon gases from an oil cracking process or other sources may be introduced into a heating zone for subjection to controlled conversion conditions of temperature and pressure, after which the heated products may be introduced into an enlarged reaction zone maintained under a substantially reduced pressure in respect to the heating zone and wherein the reactions progressing therein may be carried out in the presence of ultra violet rays, the lighter evolved vapors of reaction being thereafter subjected to fractionation, condensation and collection.

Other and further objects and advantages of the invention will become apparent from the following description and accompanying diagrammatic drawing illustrating a side-elevational view of one form of apparatus in which the invention may be carried out.

Referring to the drawing, raw oil charging stock for a cracking process may be introduced into the system from a line 1, controlled by valve 2, by a pump 3 discharging into a line 4, controlled by valve 5, leading into the upper or fractionating portion 16 of a combined fractionator and reaction chamber 6 wherein hydrocarbon vapors from a reaction zone of such process are undergoing fractionation. The raw oil, in a relatively cool state, passes countercurrent to the ascending vapors within said fractionator 16, serving to cool said vapors and condense the

relatively heavy, insufficiently converted components thereof, and, in turn, being preheated, with the vaporization of its relatively light desirable fractions, if any are contained therein. The heavier, insufficiently converted portions of said vapors and the preheated raw oil fed into said fractionator, collect in the lower portion of said fractionating section and may be withdrawn therefrom through a line 7, controlled by valve 8, to a pump 9, which discharges into a line 10, controlled by valve 11. Raw oil may, if desired, be passed directly into line 7 through line 4' and valve 5', passing thence to pump 9.

The reflux condensate and raw oil charging stock passing through said line 10, may be introduced into a suitable heating element 12, disposed within a furnace 13, wherein said condensate and preheated raw charging stock may be subjected to any desired conversion temperature and pressure, depending upon the nature and character of the oil under treatment and the end products desired. Such temperature, for example, may range from 850° F. to 1000° F., while the pressures utilized within said heating element may be of the order of about 750 pounds per square inch to about 900 pounds per square inch more or less.

After subjection to the desired conversion conditions within heating element 12, the heated products may be discharged from said heating element through a line 14, controlled by valve 15 and introduced into an enlarged reaction zone 16' preferably maintained under a substantial superatmospheric pressure which may be substantially the same or lower than the pressure maintained in the heating element, and wherein the reactions started within said heating element may progress to the desired degree of completion, sufficient time period for this purpose being allotted to the products under treatment in chamber 16'. The lighter vaporous products of reaction separate from the liquid portions

thereof, the latter being withdrawn from said reaction chamber through a line 17, controlled by valve 17' to storage or elsewhere as desired or in case the reaction is allowed 5 to progress to the stage where only coke or carbonaceous material remain as the residual product said coke or carbonaceous material may collect within the chamber to be removed through manway 16" after operation 10 of the process is completed.

The vaporous products of reaction may be introduced into fractionating chamber 16 through a line 7' containing a valve 8' interposed between said fractionator and the reaction chamber, thus enabling the fractionator to be maintained under a reduced pressure, if desired. The vapors on entering said fractionator pass upwardly therethrough, countercurrent to the downwardly flowing 15 raw oil and/or reflux condensate, as previously described, and after sufficient treatment within said fractionator, the lighter, gasoline-like portions of the vapors may be withdrawn therefrom from a suitable tray 20 in said dephlegmator or fractionator through a line 18, controlled by valve 19, and passed from said line to suitable, cooling, condensing and collecting equipment of the system (not shown). In order to assist in controlling 25 the boiling-point range of the gasoline-like fractions and the quality of the gases produced in the process, and in order to further maintain a relatively constant temperature and control thereover at the outlet 30 of said fractionator, any desired cooling medium, such as pressure distillate from a receiver of the process may be introduced into the upper portion of said fractionator from a line 20, controlled by valve 21, by pump 22, 35 discharging into a line 23 leading into a suitable spraying device (not shown) or any other distributing means disposed in the upper limits of said fractionator. In this manner, the valuable hydrocarbons constituting the 40 gasoline fractions of the process may not be subjected to retreatment with the gaseous hydrocarbons produced in this stage of the 45 process.

Hydrocarbon gases separated out in and 50 evolved from fractionator 16 may be withdrawn from the top of said fractionator through a line 24, controlled by valve 25 and introduced through said line into a secondary heating element 26 disposed within a suitable 55 furnace 27 where they may be subject to the desired retreatment of the process. Any desired temperature may be utilized within said secondary heating element 26, but preferably a temperature range of from 1200° F. to 1850° 60 F. may be employed. Pressures utilized within said secondary heating element 26 are preferably lower than those employed within the primary heating element 12, and may range from about 200 pounds per square 65 inch to about 400 pounds per square inch,

depending upon the degree or yield of acetylene or highly unsaturated hydrocarbons required.

Prior to the admission of the gases from the cracking unit to the succeeding secondary 70 heating element 26, hydrocarbon gas mixtures from other sources may be admitted from a line 24' containing a valve 25' under pressures produced if necessary by pumping 75 means not shown. Gases introduced at this point may be natural gases occurring in association with crude petroleum or otherwise, gases from a distillation of crude petroleums, gases produced in the distillation of coal or shale and from any other source. As the 80 process of the invention is separate from any particular cracking process it comprises operation upon any of the gases mentioned arising from other sources than a cracking process and may be conducted upon any of these 85 gases singly or in combinations with suitable modifications of operating conditions such as temperature and pressure to enable desired results to be obtained upon hydrocarbon gases of varying composition. 90

The highly heated hydrocarbons from secondary heating element 26 may be discharged therefrom through a line 28, controlled by valve 29 and introduced into a secondary reaction chamber 30 which is preferably maintained under a substantial vacuum. During their period of reaction within said chamber 30, the highly heated hydrocarbons are subjected to the polymerizing action of a mercury light or other source of ultra violet rays 100 31 within said chamber, leads 30' and 31' indicating electrical terminals for a lamp. Other means of subjecting the gases to the action of ultra violet light may be employed; for example, the light may be admitted 105 through quartz windows at different points in the chamber, the source of the rays being then outside the chamber. This portion of the system is largely responsible for the high yield of acetylene, which may be 40% or more 110 of the gas collected in the receiving portion of the system, and the pressure conditions employed therein to produce such acetylene or unsaturates of like nature is, as has been stated, preferably that corresponding to a 115 high degree of vacuum, or may be substantially atmospheric or only slightly sub-atmospheric.

After subjection to the desired reaction and polymerizing action of the ultra violet ray light on the unsaturates under treatment within said reaction chamber 30, condensed liquids accumulating in the bottom of the treating chamber may be withdrawn through a line 32' containing a valve 33' and depending upon the nature of these liquids they may be utilized directly as motor or other fuel or returned to a cracking zone for further conversion. When subatmospheric pressures are employed in the 120 125 130

treater a pump such as 52 may be employed to discharge these oils through a line 53 controlled by a valve 54 to any point desired. The treated vaporous products may be conducted 5 therefrom through a line 32, controlled by valve 33 and introduced into a fractionator 34 wherein the heavier and lighter portions of said products are separated, the heavier portions thereof being withdrawn 10 from said fractionator through a line 35, controlled by valve 36, by a pump 55 discharging into a line 56 controlled by a valve 57 either to a conversion zone or to storage, (such a pump being necessary as in the case of pump 52 when subatmospheric 15 pressures are employed in the system) either from the system, or returned for further treatment; while the lighter desired components from said fractionator 34 may be passed through a line 37, controlled by valve 38 into a condenser or cooler 39 wherein liquefaction and separation of gases is obtained. When vacuum is employed in the treater of the fractionator, more efficient cooling means 20 may be employed around condenser coil 39 than are usually used in oil refineries, for example, instead of water at atmospheric temperature cold brines may be circulated or the coils cooled by expansion of low boiling gases such as carbon dioxide or sulfur dioxide. The cooled products then pass from said cooler through a line 40, controlled by valve 41 into a receiver 42, wherein the liquids and gases separate. The incondensable gases 25 from the system may be withdrawn from said receiver through a line 43, controlled by valve 44 through a vacuum pump 45, which discharges into a line 46 which may lead to storage or absorption equipment. When subatmospheric pressures are used it may be 30 advisable to employ absorption equipment upon the vapors for the complete recovery of gasoline fractions though such absorption equipment is not shown in the drawing. The liquid fractions separated out within said receiver 42 may be withdrawn therefrom through a line 47, controlled by valve 48, (these containing large amounts of gasoline 35 hydrocarbons of the aromatic series) and pumped by pump 49 into a line 50 controlled by a valve 51 to any desired point.

While numerous examples of operations upon different hydrocarbon gases and results obtainable therefrom might be given, it will suffice to cite a case involving the use of cracked gases and one using natural gas, such cases being generally typical of the gases which may be employed, the cracked gases representing a class containing relatively large amounts of unsaturated derivatives and being somewhat similar to the gases obtained from shale and coal distillation and the latter type being similar to the gases obtained in the straight or non-cracking distillation of crude petroleums.

As one example, the gases produced by cracking a 30 gravity Mid-Continent gas oil at a pressure of 250 pounds per square inch and a mean reaction zone temperature of 940° F. may be retreated in a secondary heating coil at a temperature of 1600° F. and subatmospheric pressure corresponding to an absolute pressure of about 5 pounds per square inch. Under these conditions and in the presence of a source of ultra violet of sufficient intensity there may be produced an overall yield based on the gas oil charging stock of 75% gasoline boiling range hydrocarbons, these gasoline hydrocarbons being of highly aromatic nature corresponding to a benzol equivalent of 75 to 80% whereas without the use of the secondary conversion step upon the fixed gases the corresponding yield of gasoline may be only 65 to 70% with a benzol equivalent of 60%. The fixed gases constituting the final gaseous end product of the gas treating process such as leave the absorption plant as gases stripped of gasoline vapors may still be high in acetylenic hydrocarbons, at times containing as high as 20% acetylene. 70 75 80 85 90 95 100 105 110 115 120 125 130

As an example of operations conducted upon hydrocarbon gases of a more or less saturated type such as natural gas mixtures, a natural gas containing 75% of methane, 15% ethane, 5% propane and the balance higher hydrocarbons, may be heated during passage through a coil similar to 26 in the drawing to a temperature of 1200° F., a pressure of approximately 300 pounds per square inch being maintained upon the gas during its passage through the coil. The heated and partially converted gases may then be flashed into an ultra violet light treating chamber such as chamber 30 in the drawing wherein they are exposed to the light influence under a pressure of about 12 pounds below atmospheric. By this treatment may be produced a yield of 6 gallons of motor fuel per thousand feet of gas processed, this motor fuel being of a highly aromatic nature as evidenced by its high knock rating corresponding to approximately 65 to 70% benzol equivalent.

I claim as my invention:—

1. A process for treating normally incondensable hydrocarbon gases which comprises heating the same under superatmospheric pressure to a temperature of between 1200° F. and 1850° F., then substantially lowering the pressure on the heated gases and subjecting the same under the lower pressure to the action of ultra violet light.

2. A process for treating normally incondensable hydrocarbon gases which comprises heating the same under superatmospheric pressure to a temperature of between 1200° F. and 1850° F., and then exposing the thus heated gases under vacuum to the action of ultra violet light.

3. A process for producing acetylene and liquid hydrocarbon motor fuel which comprises heating the normally incondensable gases produced in the cracking of hydrocarbon oils to between 1200° F. and 1850° F. under superatmospheric pressure, then treating the gases while still hot with ultra violet light under vacuum, and separating the vapors thus formed from the gases by condensation.

In testimony whereof I affix my signature
GUSTAV EGLOFF.
